UNITED STATES PATENT OFFICE.

ULYSSES R. GRANT, OF ALAMEDA, CALIFORNIA, ASSIGNOR TO HYGIENIC SEAT COMPANY, OF SAN FRANCISCO, CALIFORNIA, A CORPORATION OF CALIFORNIA.

SANITARY TOILET SEAT.

Application filed December 18, 1923. Serial No. 681,354.

To all whom it may concern:

Be it known that I, ULYSSES R. GRANT, citizen of the United States, residing at Alameda, in the county of Alameda and 5 State of California, have invented certain new and useful Improvements in Sanitary Toilet Seats, of which the following is a specification.

The hereinafter described invention comprises a hollow sanitary toilet seat which is expressly designed for use in connection with hospitals, railway cars, and public places, although equally as well adapted for home use generally, and the object thereof is the production of a simple, 10 light, sanitary and durable closet seat, one which will withstand the hard usage to which such devices are subjected, and will not warp, crack or become affected by reason of moisture or the water standing in the bowl to which it is applied and by its 15 construction will afford the user increased room at its forward under side over that afforded by the seats now universally in use. The improved toilet seat is preferably constructed of two metallic sections or members 20 suitably stamped to the proper shape, the upper member of the seat having applied thereto an outer sanitary coating or layer 25 of hard rubber or other plastic compound. The plastic or rubber covering applied to the upper member of the seat affords a seal 30 for precluding the entrance of moisture between the unity seam line of the upper and lower sections; gives a proper finish thereto, 35 provides sufficient warmth to prevent undue chilling of the body of the user, and at the same time furnishes an antiseptic surface for the seat. The members comprising 40 the seat are suitably stamped into proper shape for a toilet seat prior to the union thereof, the inner and outer edges of the lower section are upwardly flanged to receive on their inner faces the outwardly 45 curved edges of the upper section.

To comprehend the invention, reference should be had to the accompanying sheets of drawings, wherein—

Fig. 1 is a front elevation of a closet bowl 50 with the improved seat applied thereto.

Fig. 2 is a bottom plan view of the seat removed from the closet bowl, disclosing the elastic cushions and their manner of attachment to the seat, and the raised pocket

formed in the forward portion of the bottom member of the seat.

Fig. 3 is a plan view of the seat illustrating in general the curved lines given thereto for the production of a proper shaped seat.

Fig. 4 is a transverse sectional view of 60 the seat taken on the lines $x-x$, Fig. 1 of the drawings, viewed in the direction of the longitudinally disposed arrow.

Fig. 5 is a longitudinal sectional view taken on line $y-y$ Fig. 1 of the drawings, 65 viewed in the direction of the transversely disposed arrow, particularly illustrating the channeled recess at the under side of the forward edge of the seat.

The numeral 1 is used to designate any 70 form of a toilet bowl to which the improved seat is hinged; 2 the bottom open member of the seat; 3 the upper open member thereof, and 4 the layer or coating of hard rubber applied and vulcanized to the upper member 75 3. Preferably, the bottom member 2 is stamped from a single sheet of metal, and the upper member 3 similarly stamped from a single piece of metal, the stamped members being of elliptical form. The upper 80 member 3 when stamped is in the form of a hollow elliptical shell, the upper surface thereof being gradually downwardly and inwardly curved from the outer edge portion intermediate the points 5 and 6 to produce the required outline of a toilet seat, 85 conformable to the body of a user, the material between the points 5 and 6 being slightly curved upwardly into substantially 90 an ogee swell 6', the swell being sufficient 90 to raise the points 6' to a point above the normal plane of the remainder of the seat, the uprise caused thereby tending to properly place the user of the seat. The inner edge 95 6", as in Fig. 5, is raised to a point slightly below the normal plane of the upper surface 100 of the seat while the outer edge on the same line $y-y$ is in the same plane with the remaining portion of the outer edge.

The said member 2 is from a point inwardly removed from its forward edge raised and curved upwardly and inwardly on the line 82 to provide a clearance space 8 to the under surface at such portion of the toilet seat.

The portion 83 of the member 2 lying forwardly of the space 8 lies in the same plane as the remainder of the member 2 and over-

lies the forward edge 8⁴ of the closet bowl. The inner edge 9 and the outer edge 9' of the upper member 3 of the toilet seat are slightly outwardly flanged, and the inner and outer edges 10 and 10' of the bottom member upwardly flanged and crimped onto the flanged edges of the upper member when uniting one to the other.

While preference is given to a crimped 10 seam union between the inner and outer edges of the members of the toilet seat, it is obvious that the same may be united in any suitable manner.

When the said upper and lower members 15 are united, there is produced a hollow toilet seat composed of a substantially flat bottom and an upper metallic shell section, each of approximately elliptical form, the exposed top surface of the upper member or section 20 being shaped to conform to the outline of the body of a user thereof, and provided adjacent its forward edge with an uprise or swell.

The upper elastic, plastic or hard rubber 25 covering 4 for the upper member provides a comparatively warm and antiseptic covering surface for the seat, one which removes the chill which otherwise would result from contact of the body with a metallic surface, 30 and at the same time provides a surface which may be readily cleaned.

To the under face of the member 2 the upwardly curved arms 11 are united, within the free ends of which is mounted the trans- 35 verse rod 12, which is supported and held by the hinge brackets 13, by means of which the toilet seat is hinged to the bowl 1 in the usual manner.

By reason of the seat being formed hollow 40 there is secured extreme lightness, inasmuch as the members composing the seat may be constructed of thin metal.

The clearance space or depression 8 provided in the under face of the bottom mem- 45 ber of the toilet eliminates the danger of excess fouling adjacent the forward end portion thereof.

There is provided a lid or swinging cover 14 for use in connection with the improved

toilet seat, the same being united in any suit- 50 able manner to the hinge connection between the seat and the closet bowl. Like the seat proper, the swinging lid or cover 14 is constructed of stamped metal sheets properly secured together to provide a hollow lid or 55 cover. However, the construction of the said lid or cover forms no portion of the present invention, consequently a detailed description need not be given at this time, 60 inasmuch as any suitable form of a cover or lid may be employed in connection with the improved seat.

I claim:

A toilet seat comprising a pair of cooper- 65 ating sections of sheet material formed to provide a hollow substantially elliptical seat, one of said sections forming a bottom part of relatively wide flat form, said bottom part having an area of substantially 70 semi-circular shape extending from the inner edge of the seat forwardly, said area ex- 75 tends upwardly in curved relation from the juncture with the flat adjacent portion of the part, to the central portion of said area at the inner edge thereof and terminat- 80 ing in a plane contiguous to the horizontal plane of the upper edge of the seat, and the other of said sections forming the upper part having the edge portions curved down- 85 wardly from the central portion in a pre- 90 determined manner, the forward portion of said upper part being formed with an area extending substantially above the horizontal plane of the upper edge of the seat and spaced above the area of the bottom part, 95 said last-mentioned area having the portion of greatest height adjacent the inner edge of the seat and having the remaining portions of the area curving downwardly in all di- 90 rections into the curvature of the remaining portion of the part to provide a body receiv- 95 ing contour in said seat, the edges of said sections being formed into interlocking co- operation to retain the sections in seat forming relation.

In testimony whereof I have signed my name to this specification.

ULYSSES R. GRANT.
